UNITED STATES PATENT OFFICE.

CHARLES K. HILL, OF CLEVELAND, OHIO, ASSIGNOR TO THE H. C. TACK COMPANY, OF CLEVELAND, OHIO, A CORPORATION OF OHIO.

DESIGN FOR A TACK OR NAIL.

54,088.

Specification for Design.

Patented Nov. 4, 1919.

Application filed January 6, 1919. Serial No. 269,955. Term of patent 14 years.

To all whom it may concern:

Be it known that I, CHARLES K. HILL, a citizen of the United States, and resident of Cleveland, county of Cuyahoga, and State of Ohio, have invented a new, original, and ornamental Design for a Tack or Nail, of which the following is a specification, reference being had to the accompanying drawing, forming part thereof.

In said annexed drawing:—

Figure 1 is a plan view; Fig. 2 is a side

elevation; and Fig. 3 is a front elevation showing my new design.

I claim:—

The ornamental design for a tack or nail, as shown.

Signed by me, this 31 day of December, 1918.

CHARLES K. HILL.
